Paul O. Kock, Columbus, Ohio, assignor to Bituminous Coal Research, Inc., Pittsburgh, Pa., a corporation of Delaware

Application August 9, 1956, Serial No. 603,088

10 Claims. (Cl. 122—265)

This invention relates to a boiler. More particularly, it pertains to a new kind of water-tube boiler capable of burning coal and other fuels with relatively higher efficiency and greater economy of space.

Boilers of the water-tube type for the generation of steam or the supplying of quantities of hot water for industrial and other purpose have been extensively used. However, a number of difficulties have attended prior water-tube boiler practices. Where coal has been the fuel, for example, the boiler foundation base, or the firebox space within the lower part of the boiler shell, or both, has been relatively high to try to increase the length of the path of travel of the gases, particularly before encountering any substantial cooling surface. Otherwise, such surface might become fouled by the condensation thereon of volatiles in gases from coals or briquetted solid fuels. In some cases such volatiles might even pass through a boiler with attendant hazard due to a possibility of explosion and/or with the creation of smoke. In some situations the space economy of such water-tube boilers might be so poor as to cause them to be rejected in favor of lower headroom boilers such as exist in the fire-tube boiler field. In other cases, prior water-tube boilers have utilized water tubes of different lengths in a single boiler and/or have required a special construction not readily lending itself to a design for flexibility in capacity or duplication for repeated installations.

In my invention disclosed herein, deficiencies of prior boiler practices have been overcome. Thus, in water-tube boiler embodiments of my invention, there is a material economy in the space requirement such as headroom. Moreover, the path traveled by gases is relatively markedly lengthened with heightened assurance of complete combustion and inhibition of any explosion hazard or smoke nuisance even when burning a solid fuel like bituminous coal or the like. Thus, clusters of water tubes may thereby be positioned far enough back in the gas flow path to prevent material condensation and/or fouling of tube surfaces by such condensable volatiles, for example, as might originally have been present. Tubes utilized in embodiments of this invention preferably are made the same length with relative improvement in water circulation pattern and relatively higher heating efficiency because of the new construction. Still further, boiler embodiments of my invention are flexible in terms of boiler capacity design alterable to a greater capacity, e. g., by the addition of one or more vertical banks of water tubes without changing the over-all length or character of such a boiler embodiment.

Other objects and advantages will be apparent from the following description and from the accompanying drawings, which are illustrative of one embodiment only, in which

Figure 1 is a view in side elevation of one embodiment of a water-tube boiler constructed in accordance with this invention;

2

Figure 2 is a front view of the boiler shown in Figure 1;

Figure 3 is a rear view of the boiler shown in Figure 1;

Figure 4 is a plan view of the boiler shown in Figure 1 taken along line IV—IV of Figure 7;

Figure 5 is a view in section taken along line V—V of Figure 4;

Figure 6 is a view in section taken along line VI—VI of Figure 7; and

Figure 7 is a view taken along line VII—VII of Figure 5.

Referring to the drawings, a water-tube boiler 10 constitutes one embodiment of my invention. It is shown with a commercial form of automatic stoker 11 having

a shaker grate 12 to supply solid fuel like coal or carbonaceous briquettes to boiler 10 for burning therein, although other fuels like fuel gas and oil may successfully be burned in a new boiler of this invention. Boiler 10 is positioned on a relatively low foundation or base 13, the main structural members of which, if desired, may be downward extensions of the shell of boiler 10. Ashes may be removed from boiler 10 by an ash removal conveyor 14 when solid fuel is burned therein and combustion air at suitable pressure may be supplied as under-grate primary combustion air by a forced draft blower 15 or by an induced draft fan (not shown) in the flue connection 16, or by both, as desired. Flue 16 communicates with a gas dome 17 in boiler 10 through a breeching connection 18, the other end of flue 16 entering a stack for waste gaseous products of combustion. Steam may be generated by boiler 10 and collected in a steam space 19 above the water surface 20. Such steam may be discharged through a main steam outlet 21 connected to a main steam pipe 22.

A coupling 23 communicates with the interior of water leg 46 near the bottom 24 so that feed water from a pipe 25 may be supplied to boiler 10 when valve 26 is opened. Coupling 23 may, alternatively, be connected to a drain pipe 27 when a plug valve 28 is opened to drain

or blow out some or all of the water in boiler 10. Clean-out doors 29 may be provided on one or both sides of embodiment 10 of my new boiler and a furnace access door 30 may be provided with other suitable access and inspection opening provisions including front access doors 31 and 32 respectively on boiler 10 and below stoker 11, as will be readily understood by those having skill in the boiler art to whom this invention is disclosed.

Boiler 10 is provided with a hollow shell made up of an outer shell 33 and an inner shell 34. Outer shell 33 may have a top 35 in the form of a wagon top or other form, side plates 36, a front plate 37 and a rear plate 38. Front and rear plates 37 and 38 may be respectively provided with plug sheets 39 and 40 respectively pierced in registry with the water-tubes in boiler 10, such piercings being tapped and plugged by threaded plugs 41 which can be removed when the insides of particular water tubes are to be cleaned or particular water tubes are to be replaced through the openings in the plug sheets 39 and 40, an expander tool generally being used to expand the ends of the water tubes into tight binding relation to the front and rear tube sheets 42 and 43 respectively comprising the front and rear plates of inner shell 34. The plates 42 and 43 are respectively joined at the bottom to plates 37 and 38 while side plates 44 of inner shell

34 are respectively joined at the bottom to side plates 36 of outer shell 33 to provide front and rear water legs 45 and 46 respectively and side water legs 47, in boiler 10. The inner and outer shells 33 and 34 may otherwise be suitably stayed in spaced relation to provide the water and steam space required or the water space required where a boiler of this invention is to be used as a hot water supplier without the generation of steam.

70

In the illustrated embodiment, a vertical water wall partition 48 is provided extending between front water leg 45 and rear water leg 46 extending in height from the top of base 13 approximately midway to the level 49 of the top row of water tubes in boiler 10. The top 50 of partition 48 is preferably pitched or tilted upwardly from rear to front at the slope given to the water tubes in boiler 10. Water partition 48 is provided with pipe connections to the front and rear water legs 45 and 46 or separately supplied with a supply of circulating water, as desired. Further, the lower edge of water partition 48 may be extended downwardly into base 13, especially where a lower grate than grate 12 may be utilized, such as might be the case when an underfeed stoker is used for the supplying and burning of solid carbonaceous fuel in a new boiler of this invention. Partition 48 is continued upwardly by a plate partition or baffle 51 extending to level 49 in height and extending in length from tube sheet 42 to the forward edge 52 of a partition opening 53 in the longitudinal plane of baffle 51.

A fire zone 54 is provided in boiler 10 between the left side water leg 47, grate 12, partition 48 and a roof in the form of a baffle 55 of cast refractory or laid block which may be supported in part by a horizontal row 56 of water tubes and the top of partition 48, such roof baffle extending from rear water leg 46, that is, from rear tube sheet 43, to its transverse forward edge 57 defining an opening 58 for gaseous combustion materials and products leading from longitudinally extending fire zone 54 into a longitudinally extending radiant zone 59 superposed thereabove in the boiler 10 embodiment.

Radiant zone 59, as shown, is bounded by roof baffle 55 and tube row 56 along the bottom, by water leg 47 on the left, by a horizontal row 60 of water tubes extending laterally to plate baffle 51 and by a ceiling slab 61 on the top, and, by a vertical row 62 of water tubes on the right adjoining baffle 51. Ceiling slab 61 may be made of cast refractory or laid refractory blocks supported on the water tubes at level 49 as shown. The ceiling slab extends wholly across the radiant zone 59 and from one end thereof to the other and also across the top of water tube cluster zones 63 and 64, save for an opening 65 therein for the passage of waste gaseous combustion products into gas dome 17. Thus, it will be noted that flame and gaseous products of combustion are provided with a relatively long travel in fire zone 54 and radiant zone 59 by which time combustion of all volatiles should be complete before there is material interposition of water-cooled tube surfaces in the flow path of such gaseous products with the result that condensation on such water-cooled surfaces and fouling thereof is inhibited or wholly avoided even when relatively high-volatiles-containing solid or other fuels are utilized.

The gaseous products of combustion then pass through partition opening 53 into tube cluster zone 63. The vertical banks 66 of water tubes in cluster zones 63 and 64 may extend downwardly from level 49 to a position close to the bottom of boiler 10. All of such tubes, as are all of the tubes in boiler 10 inclusive of the tubes in rows 56, 60 and in bank 62, are of equal length. The respective ends of the tubes extend through and are sealed in the respective tube sheets 42 and 43 around the outside of the ends of such water tubes so that a relatively high velocity water circulation pattern is achieved with water flowing downwardly in the rear water leg 46, entering the rear lower ends of all of the water tubes and exiting at the front ends of such water tubes in front water leg 45 before ascending to pass over and across the top of inner shell 34 beneath the steam space 19. The water surface 20 is preferably maintained at the water line set for boiler 10 by automatic feed water supply means which control the opening and closing of valve 26. In addition, other water paths will occur with movement of water in the side water legs 47 in a generally upward direction, some quieter recirculation being

possible at the vertical corners between the inner and outer shells 33 and 34 which has value in affording a place for the deposit of any sediment which can be washed out periodically when wash-out plugs 67 are removed for such purpose.

A refractory floor slab 68, which may be cast refractory or laid refractory brick, is provided to close the bottom of cluster zones 63 and 64. Slab 68 may be supported on a plate 69 supported on base 13 or fastened to the underside of boiler 10. Zones 63 and 64 may be partially separated by a transverse curtain baffle 70 extending across the full width of those zones and downwardly from ceiling slab 61 to lower edge 71 above slab 68 so as to provide an opening under edge 71 from zone 63 into zone 64 for the gaseous products of combustion which give up further heat to the tubes in banks 66 in zone 64 before exiting as through ceiling opening 65 into gas dome 17 and from thence through breech connection 18 into flue 16 and the stack which normally would be connected to flue 16. The heating gases by having to pass beneath edge 71 have their paths of travel in the cluster zones 63 and 64 lengthened for additional increase in heating efficiency provided by a boiler such as boiler 10 with its materially increased path of heating gas travel starting in fire zone 54 as the first pass, then going through the fire zone opening forwardly of edge 55 to enter the second pass extending the length of radiation zone 59 where additional heat is given up to the screening tubes 60 and 62 before the heating gases pass through the partition opening 53 and move in their third pass over the clustered water tubes in cluster zone 63, the fourth pass coming as the heating gases pass the curtain baffle 70 and move through the clustered water tubes in cluster zone 64 with the fifth pass for such gases through gas dome 17, providing additional heat release to the water through a crown sheet 72 at the top of inner shell 34. The respective gas openings between zones are preferably sized to take care of change in volume of gaseous flow therethrough occasioned by combustion and heat transfer which occurs in the course of flow travel in new boilers made in accordance with this invention.

Although various fuels may be utilized in a boiler made in accordance with this invention, boiler 10 is illustrated as being automatically supplied with solid fuel like coal by a stoker 11 having a coal hopper 73 above the forward end of its grate 12, a rotating feed roller 74 being turned by an electric motor 75 mounted on a stoker base 76 which may be on an extension of base 13. Grate 12 may be in the form of a shaker grate slidable back and forth on ways 77 supported on the portion of plate 69 extending across the bottom of fire zone 54, such ways 77 terminating at the forward edge of an ash pit 78 having sloping sides to funnel ashes into an open-sided conveyor trough 79 in which a conveyor screw 80 lifts them through a conveyor tube 81, which is a part of the ash removal conveyor 14, so that they can be discharged through a spout 82. An electric motor 83 may be provided and connected with the shaft of screw 80 to turn it when boiler 10 is operating on coal.

Grate 12 extends through a front opening 84 in the boiler shell at the bottom of front water leg 45 and may be shaken back and forth in conventional manner by a grate slide end 85 connected by a shaker link 86 to a rocking arm 87 rocked by an eccentric connection thereof to an electric motor 88. Combustion air for the burning of fuel on grate 12 in fire zone 54 enters base 13 through opening 89 beneath slab 68 and enters the underside of grate 12 past the front end 90 of a side wall 91, extending forwardly along the side of ash pit 78. Such combustion air may be at ambient temperature, or pre-heated, and may receive heat in passing beneath the floor of the cluster zones 63 and 64. Further, if desired, over-fire combustion air may, if desired, be supplied into fire zone 54 by nozzles or otherwise through one or more water legs of boiler 10.

Various modifications may be made in the illustrated embodiment of my invention and in other embodiments thereof without departing from the spirit of my invention or the scope of the appended claims.

I claim:

1. In a water tube boiler, in combination, a hollow shell having water legs at the sides and ends, the inside of said shell defining an interior space for said boiler, a longitudinally extending fire zone in said space, a lower vertical water-cooled partition defining the inner side of said fire zone, said partition being intermediate the sides of said space, a horizontal refractory roof baffle defining the top of said fire zone, said roof baffle being intermediate the top and bottom of said space, a radiant zone extending the length of said space in superposed relation to said fire zone, an upper vertical partition defining the inner side of said radiant zone, said upper partition being intermediate the sides of said space, a horizontal refractory ceiling defining the top of said radiant zone, said ceiling being in the upper portion of said space adjacent between the sides of said boiler but below the inside of the top of said shell to form a gas dome, said fire zone and radiant zone having a passage therebetween at one end of said space to provide a vertical re-entrant turn for gases passing from said fire zone to said radiant zone, water tubes extending the length of said boiler in cluster zones in longitudinal registry in said space on the other side of said partitions from said fire and radiant zones respectively, said upper partition having a passage from said radiant zone at the other end of said space into the adjacent one of said cluster zones to provide a horizontal re-entrant turn for gases passing from said radiant zone into said cluster zone, a transverse curtain baffle extending downwardly from said ceiling and positioned intermediate the ends of said tubes in said cluster zones, said curtain baffle having its lower edge spaced above the bottom of said cluster zones and below said passage through said upper partition to provide a vertical turn for gases passing from one cluster zone to another, and an opening in said ceiling for gases from said cluster zones to pass into said gas dome on the other side of said curtain baffle from said passage from said radiant zone, and a flue connected to said gas dome for gases leaving said boiler, said flue being spaced from said opening through said ceiling into said gas dome.

2. In a water tube boiler, in combination, a hollow shell having water legs at the sides and ends, the inside of said shell defining an interior space for said boiler, a longitudinally extending fire zone in said space, a lower vertical partition defining the inner side of said fire zone, said partition being intermediate the sides of said space, a horizontal roof baffle defining the top of said fire zone, said roof baffle being intermediate the top and bottom of said space, a radiant zone extending the length of said space in superposed relation to said fire zone, an upper vertical partition defining the inner side of said radiant zone, said upper partition being intermediate the sides of said space, a horizontal ceiling defining the top of said radiant zone, said ceiling being in the upper portion of said space adjacent but below the inside of the top of said shell to form a gas dome therebetween to provide a vertical re-entrant turn for gases passing from said fire zone to said radiant zone, water tubes extending the length of said boiler, a cluster zone in said space on the other side of said partitions from said fire and radiant zones respectively, said upper partition having a passage from said radiant zone into said cluster zone to provide a horizontal re-entrant turn for gases passing from said radiant zone into said cluster zone, and an opening in said ceiling for gases from said cluster zone to pass into said gas dome after passing through said cluster zone, and a flue connected to said gas dome for gases leaving said boiler, said flue being spaced from said opening into said gas dome.

3. In a water tube boiler, in combination, a hollow shell having water legs at the sides and ends, the inside

of said shell defining an interior space for said boiler, a longitudinally extending fire zone in said space, a vertical partition defining the inner side of said fire zone, said partition being intermediate the sides of said space, a horizontal roof baffle defining the top of said fire zone, said roof baffle being intermediate the top and bottom of said space, a radiant zone extending the length of said space in adjoining relation to said fire zone, said fire zone having an opening for passing gases into said radiant zone, a vertical partition defining the inner side of said radiant zone, a water tube cluster zone adjoining said radiant zone, water tubes in said cluster zone, a ceiling defining the top of said cluster zone, said ceiling being in the upper portion of said space adjacent but below the inside of the top of said shell to form a gas chamber therebetween, said radiant zone having an opening for passing gases into said cluster zone, said two first-mentioned openings being spaced from each other, said cluster zone having an opening for passing gases into said gas chamber after said gases have passed from said radiant zone and through said water tubes in said cluster zone, and a flue connected to said gas chamber for gases leaving said boiler.

4. In a water tube boiler, in combination, a hollow shell having water legs at the sides and ends, the inside of said shell defining an interior space for said boiler, a longitudinally extending fire zone in said space, a partition defining the inner side of said fire zone, said partition being intermediate the sides of said space, a horizontal roof baffle defining the top of said fire zone, said roof baffle being intermediate the top and bottom of said space, a radiant zone extending the length of said space in adjoining relation to said fire zone, said fire zone having an opening for passing gases into said radiant zone, a partition defining the inner side of said radiant zone, a water tube cluster zone adjoining said fire and radiant zones, water tubes in said cluster zone extending the length of said boiler, a horizontal ceiling defining the top of said cluster zone, said ceiling being in the upper portion of said space adjacent but below the inside of the top of said shell to form a gas dome therebetween, said radiant zone having an opening for passing gases into said cluster zone, said two first-mentioned openings being spaced from each other, said cluster zone having an opening for passing gases into said gas dome after said gases have passed from said radiant zone and through said water tubes in said cluster zone, baffle means in said cluster zone to force gases to pass therethrough in a bent path, and a flue connected to said gas dome for gases leaving said boiler.

5. In a boiler, in combination, a double shell defining an interior space extending substantially for the length, width and height of the inside of said shell, at least the ends of said shell defining water legs adjacent the ends of said interior space, a partition extending the length of said space intermediate the sides of said shell, said partition having an opening therethrough adjacent one end thereof, clusters of substantially straight water tubes extending longitudinally for the length of said boiler on one side of said partition, the respective ends of said tubes being supported by and being in open communication with said end water legs of said shell, a roof baffle extending laterally across said space on the other side of said partition intermediate the top and bottom of said space, said roof baffle having an opening therethrough adjacent the other end of said space from said one end, a ceiling extending across all of said space adjacent the level of the top of said tubes, said ceiling having an opening therein above said tubes in spaced relation to said opening through said partition, and means for supplying and combusting fuel in said space below said roof baffle.

6. In a water tube boiler, in combination, a double shell defining an interior space extending substantially for the length, width and height of the inside of said shell, at least the ends of said shell defining water legs adja-

cent the ends of said interior space, a vertical partition extending the length of said space intermediate the sides of said shell, clusters of substantially straight water tubes extending longitudinally for the length of said boiler on one side of said partition, the respective ends of said tubes being supported by and being in open communication with said end water legs of said shell, a horizontal roof baffle extending laterally across said space on the other side of said partition intermediate the top and bottom of said space, said partition having an opening therethrough adjacent one end thereof and above said roof baffle, a horizontal ceiling extending across all of said space adjacent the level of the top of said tubes, said ceiling having an opening therein above said tubes in spaced relation to said opening through said partition, the space between said ceiling and roof baffle forming a longitudinally extending radiant zone, said roof baffle having an opening therethrough into said radiant zone and adjacent the other end of said space from said one end, and means for supplying and combusting fuel and air in said space below said roof baffle.

7. In a water tube boiler, in combination, an outer shell, an inner shell, said shells being connected in spaced relation to provide front and rear water legs and side water legs, said inner shell having a crown sheet below the top of said outer shell, a lower vertical water-cooled partition extending between the front and rear water legs and from the bottom of said boiler upwardly about midway of the height of the top tube level in said boiler, said partition sloping upwardly from one end to the other, an upper vertical partition extending from said front water leg rearwardly to a position beyond but adjacent the midlength of said boiler and from the top of said water-cooled partition to said level, the distance rearwardly of said upper partition to said rear water leg and between the top of said partition and said level forming an opening between a radiation zone and a tube cluster zone, water tubes extending between said front and rear water legs in said cluster zone, a horizontal roof baffle extending laterally from the rear water leg forwardly to a position beyond but adjacent the forepart of said boiler, a row of relatively widely and laterally spaced water tubes extending between said front and rear water legs in supporting relation to said roof baffle, a vertical bank of water tubes in said radiation zone extending between said front and rear water legs substantially in the plane of said lower partition and next to said upper partition, said vertical bank extending from the top of said partition to said top tube level, a ceiling slab of refractory extending from one side to the other side inside said inner shell in spaced relation below said crown sheet next to said top tube level to form a gas dome between said ceiling slab and said crown sheet, laterally spaced water tubes across said top tube level in supporting relation to said ceiling slab, a transverse curtain baffle extending between said partitions and the side water leg on the side thereof away from said roof baffle, said curtain baffle extending downwardly from said ceiling slab to a position adjacent the lower water tubes in said cluster zone to provide an opening beneath the lower edge of said curtain baffle between the respective portions of said tubes in said cluster zone on each side of said curtain baffle, said ceiling slab having an opening into said gas dome the width of said cluster zone and adjacent said front water leg to permit gases from said cluster zone to enter the gas dome, a flue at the other end of said gas dome, all of said water tubes extending through the front and rear tube sheets at the front and rear of said inner shell, said water tubes, roof baffle and ceiling slab being tilted upwardly somewhat in a direction proceeding from rear to front, a steam outlet in the top of said outer shell in communication with said water legs, means for supplying and combusting solid fuel in the space below the level of said roof baffle, means for automatically removing ashes from said boiler at the rear, and means

for causing combustion air to pass into said space below the level of said roof baffle.

8. In a water tube boiler, in combination, a hollow shell having front and rear water legs, a lower vertical partition extending between the front and rear water legs and from the bottom of said boiler upwardly about midway of the height of the top tube level in said boiler, an upper partition extending from one of said water legs to a position beyond but adjacent the midlength of said boiler and from the top of said lower partition to said level, said upper partition having an opening between the top of said lower partition and said level to connect a radiation zone and a tube cluster zone, water tubes in said cluster zone, a roof baffle extending laterally from one of said water legs to a position beyond but adjacent one end of said boiler, means for supporting said roof baffle, a ceiling slab extending from one side to the other side inside said shell in spaced relation and below the top of said shell next to said top tube level to form a gas chamber above said ceiling slab, means for supporting said ceiling slab having an opening into said gas chamber for the entry of gases from said cluster zone, a transverse baffle in said cluster zone intermediate the ends of said water tubes and having an opening between the respective portions of said tubes in said cluster zone on each side of said transverse baffle, means for supplying and combusting fuel and air in the space below the level of said roof baffle, and flue means communicating with said gas chamber.
9. In a water tube boiler, apparatus comprising, in combination, a shell defining an interior space for said boiler, a longitudinally extending generally vertical partition within said shell dividing said interior space into two portions, said partition having an opening adjacent one end of said space to provide communication between said portions, generally horizontal baffle means across said portion of said interior space on one side of said partition, said baffle extending from the end of said space adjacent said opening to a position spaced from the other end of said space, further baffle means positioned on the other side of said partition to divide the portions of said interior space on said other side of said partition into a plurality of zones, one of them adjacent to said first-named opening and the other removed from said first-named opening, said further baffle means providing an opening through which said zones communicate, said last-named opening being spaced from said first-named opening, flue gas exhaust means connected to said zone removed from said first-named opening, straight water tube means extending longitudinally through said interior space on both sides of said partition, means for providing a fire on one side of said partition below one of said baffle means, and means interconnecting said water tubes for the circulation of water therethrough, whereby a low headroom straight water tube boiler is provided with sets of passes for heating gases in side-by-side relation.
10. In a water tube boiler, apparatus comprising, in combination, a shell defining an interior space for said boiler, a longitudinally extending generally vertical partition within said shell dividing said interior space into two portions, said partition having an opening adjacent one end of said space to provide communication between said portions, baffle means positioned on one side of said partition to divide that portion of said interior space into a plurality of zones, one of them adjacent to said first-named opening and the other removed from said first-named opening, said baffle means providing an opening through which said zones communicate, said last-named opening being spaced from said first-named opening, a further zone extending longitudinally in said interior space above both sides of said partition, said further zone being in communication with said zone removed from said first-named opening, substantially straight water tube means extending longitudinally through said interior space

on both sides of said partition, means adapted to support a fire on that side of said partition away from said first-named zones, means interconnecting said water tubes for the circulation of water therethrough and means for removing flue gases from said further zone.
